US00D464327S

(12) **United States Design Patent** (10) Patent No.: **US D464,327 S**
Frank, Jr. (45) Date of Patent: ** Oct. 15, 2002

(54) **RESISTIVE MOTOR SPEED CONTROL**

(75) Inventor: **Kenneth D. Frank, Jr.**, North Richland Hills, TX (US)

(73) Assignee: **Molded Products Company**, Haltom City, TX (US)

(**) Term: **14 Years**

(21) Appl. No.: **29/139,217**

(22) Filed: **Mar. 27, 2001**

(51) LOC (7) Cl. **13-03**

(52) U.S. Cl. **D13/162; D14/188**

(57) **CLAIM**

The ornamental design for a resistive motor speed control, as shown and described.

DESCRIPTION

FIG. 1 is an isometric view of the top, the front end and one side of a resistive motor speed control showing my new design.

FIG. 2 is an isometric view of the bottom, the front end, and the same side as that shown in FIG. 1.

FIG. 3 is an isometric view of the top, the rear end, and a side opposite that shown in FIGS. 1 and 2.

FIG. 4 is an isometric view of the bottom, the rear end, and the same as that shown in FIG. 3.

FIG. 5 is a plan view of the top of the resistive motor speed control.

FIG. 6 is a plan view of the front end of the resistive motor speed control.

FIG. 7 is a plan view of a side of the resistive motor speed control which is the same side as that shown in FIGS. 3 and 4.

FIG. 8 is a plan view of the bottom of the resistive motor speed control.

FIG. 9 is a plan view of the rear end of the resistive motor speed control; and,

FIG. 10 is a plan view of a side of the resistive motor speed control which is the same side as that shown in FIGS. 1 and 2.
